UNITED STATES PATENT OFFICE.

FRANK H. LAMB, OF HOQUIAM, WASHINGTON.

GRIPPING DEVICE.

SPECIFICATION forming part of Letters Patent No. 758,260, dated April 26, 1904.

Application filed December 29, 1903. Serial No. 187,007. (No model.)

To all whom it may concern:

Be it known that I, FRANK H. LAMB, a citizen of the United States, residing at Hoquiam, in the county of Chehalis, State of Washington, have invented certain new and useful Improvements in Gripping Devices, of which the following is a specification, reference being had therein to the accompanying drawings.

This invention relates to a gripping device particularly adapted to be used with wire or other rope.

The invention has for an object to provide a main contact-shoe having a separate coöperating shoe pivotally mounted thereon opposite the contacting face of the main shoe, whereby an extended gripping-surface is provided and an automatic contact gripping stress applied to the wire or rope when the separate shoes are thrown into contact therewith.

A further object of the invention is to provide a novel construction of operating-levers whereby the strain of drawing the separate shoes into contact with material operates toward the opposite ends of the main shoe, giving also a compound leverage of great force in the gripping contact and from which contact the levers may be released by slackening a tension-rope.

Other and further objects and advantages of the invention will be hereinafter set forth and the novel features thereof defined by the appended claims.

In the drawings, Figure 1 is an elevation of the invention applied to a rope or cable. Fig. 2 is a plan thereof. Fig. 3 is an end view at the right of Fig. 1. Fig. 4 is a modified form of the device, and Fig. 5 is a further modification thereof.

Like letters of reference refer to like parts in the several figures of the drawings.

The main shoe A is provided with suitable contact-face A', which may be of any desired configuration for gripping the rope, cable, or other object to which the device is applied. Coöperating with the main shoe one or more pivotally-mounted shoes may be used—for instance, in Fig. 1 separately-mounted shoes B and C, the former being pivoted at the upper end of the lever A² by means of the pivot A³, said lever being pivoted to the shoe A at

the point A⁴, and the lower free end A⁵ of the lever being connected by the pivot A⁶ with the arm A⁷, which at its upper end is pivoted at A⁸ to the opposite independent shoe C. The shoe B is provided upon its under surface with suitable contact-face B', adapted to engage the rope or cable D, as shown in Fig. 3, while the shoe C is provided with a similar face C' at the opposite end of the main shoe A. This shoe C is also formed with a suitable connection or link A⁸, for instance, provided with an eye C² for the tension-rope C³, by which it may be drawn into contact with the rope or cable to be gripped.

The lever and arm may be duplicated upon opposite sides of the shoes, as shown, or one set may be omitted, if desired. The pivot A⁶ may also comprise a bolt having its head A⁹ countersunk upon the inner face of the lever and held against rotation by a pin or fastening A¹⁰.

In the modification shown in Fig. 4 the two shoes B and C are replaced by a single shoe D, pivoted to lever A² at D' and at its opposite end D² extended beneath a contact-pin D³, which has a sliding contact on the end of the shoe. A connection-link D⁴ is also carried by this pin to receive a suitable line, as C³ in Fig. 1.

In Fig. 5 a further modification is shown, in which the lever A² is provided at its upper end with a contact-roller E', adapted to travel upon the free end E² of the shoe E, while the opposite end thereof is pivotally connected at E³ to the arm A⁷ and beyond said arm provided with a connecting-eye E⁴.

In the operation of the invention it will be seen that when strain is applied to the tension-line the shoe connected thereto will, through the arm and lever, be drawn longitudinally downward toward one end of the main shoe, which motion is transmitted through the arm to the free end of the lever carrying or contacting with the shoe, which thus travels downward and provides a gripping-contact at each end of the main shoe. When two upper shoes are used, as in Figs. 1 to 3, they move away from each other toward the opposite ends of the main shoe. An important feature of the invention is that it automatically "sets" 100

in contact with the rope or wire without any preliminary adjustment of either of the devices, and as soon as the tightening strain is applied the gripping stress then increases with 5 the strain, however great the latter may be. Furthermore, the device may be readily disengaged from the rope or wire without hammering, as however tightly it may be gripped the slackening of the tension-line will permit 10 the disengagement of the separate movable shoes. Another important feature of the invention is the long bearing area, whereby the wear upon the rope or cable is very much reduced and the strain removed from a single 15 point, so that the cutting of the strands of the cable is prevented.

It will be obvious that changes may be made in the details of construction and configuration without departing from the spirit of the 20 invention as defined by the appended claims.

Having described my invention and set forth its merits, what I claim, and desire to secure by Letters Patent, is—

1. In a gripping device, a main shoe, and a 25 separate coöoperating shoe opposite the contact-face of the main shoe and pivotally supported therefrom to travel toward and from the main shoe and longitudinally thereof.

2. In a gripping device, a main shoe, and a 30 separate coöoperating shoes opposite the contact-face of the main shoe and pivotally supported thereon to travel toward the opposite ends of the main shoe.

3. In a gripping device, a main shoe, a lever 35 pivoted thereon, a separate shoe pivoted

at one end of the lever opposite the contact-face of the main shoe, an arm extending from the opposite end of the lever for operating the same, and a separate shoe pivoted to the free end of said arm.

4. In a gripping device, a main shoe, a lever pivoted thereon, a separate shoe pivoted 40 at one end of the lever opposite the contact-face of the main shoe, an arm extending from the opposite end of the lever for operating 45 the same, a separate shoe pivoted to the free end of the said arm, and a connecting-link carried by the free end of said arm.

5. In a gripping device, a main shoe, a lever pivoted upon one side thereof, a separate 50 contacting shoe pivoted at one end of said lever opposite the contact-face at one end of the main shoe, a separate shoe at the opposite end of the main shoe, and an arm pivoted at one side of the last-mentioned separate shoe 55 and to the free end of said lever.

6. In a gripping device, a main shoe, a lever pivoted thereon, an arm pivoted at one end of said lever, a coöperating shoe, means carried by the free end of the lever for contacting with said coöperating shoe, and a connection for imparting movement to the free end of said arm.

In testimony whereof I affix my signature in presence of two witnesses.

FRANK H. LAMB.
